UNITED STATES PATENT OFFICE.

WILLIAM H. KRUEGER, OF MILWAUKEE, WISCONSIN, ASSIGNOR TO HARRY F. KRUEGER, OF MILWAUKEE, WISCONSIN.

CARBURETER.

1,183,081.

Specification of Letters Pat.

Patented May 16, 1916.

Application filed June 10, 1912. Serial No. 702,714.

To all whom it may concern:

Be it known that I, WILLIAM H. KRUEGER, a citizen of the United States, residing in Milwaukee, in the county of Milwaukee and 5 State of Wisconsin, have invented new and useful Improvements in Carbureters, of which the following is a description, reference being had to the accompanying drawings, which are a part of this specification.

10 This invention relates to improvements in carbureters for internal combustion engines.

One of the objects of the invention is to provide a carbureter which is simple in construction, economical in the use of volatile 15 fluid and is easily controlled.

A further object of the invention is to provide a carbureter with a multiplicity of valve controlled jet nozzles fed from a single float controlled chamber and which 20 has independent carbureting chambers provided with inlet and outlet check valves.

A further object of the invention is to provide a carbureter in which the independent carbureting chambers are in communication 25 with a single feed pipe which is adapted to be connected to the intake port of an internal combustion engine.

A further object of the invention is to provide a carbureter, in which an independent 30 supply nozzle and a carbureting chamber are provided for supplying and vaporizing a minimum amount of the volatile fluid for starting an engine and for running at reduced speeds.

35 A further object of the invention is to provide a carbureter in which the multiplicity of carbureting chambers are opened and closed in successive order to supply the power medium to the intake pipe.

40 A further object of the invention is to provide a carbureter in which the direct communication of the carbureting chambers to the feed pipe serves to greatly eliminate condensation and thereby facilitate the 45 starting of the engine.

A further object of the invention is to provide a carbureter with check valves having tapered seats to permit fine gradations of opening and greater flexibility of control.

50 With the above, and other objects in view, the invention consists of the improved carbureter and its parts and combinations as set forth in the claims.

In the accompanying drawing in which 55 the same reference characters indicate the

same parts in all of the views: Figure 1 is a vertical sectional view of the improved carbureter taken on line 1—1 of Fig. 2; Fig. 2 is a top view thereof; Fig. 3 is a vertical sectional view thereof taken on line 3—3 of Fig. 2; and Fig. 4 is a horizontal sectional view of the upper portion of the carbureter taken on line 4—4 of Fig. 1.

Referring to the drawings the numeral 8 indicates the float chamber and 9, 10 and 11 the three carbureting chambers formed integral therewith and spaced equi-distant from each other. Nozzles 12 extending at an angle into the carbureting chambers from the float chamber and controlled by needle valves 13 which extend through the bottom portion of said float chamber, are adapted to supply the volatile fluid to said carbureting chambers.

The lower portions of the carbureting 75 chambers are provided with spring controlled check valves 14 which are adapted to normally close the air inlet openings 15 formed in the bottom walls of the carbureting chamber. These check valves and 80 their seats are tapered to provide for a gradual opening of said valves and a more direct passage for the air.

A float 16 positioned in the float chamber and provided with a valve 17 serves to automatically maintain a predetermined volatile 85 fluid level within the chamber slightly below the nozzle openings. The valve 17 is adapted to close the volatile fluid inlet duct 18 and stop the flow when the fluid reaches 90 the desired level. This duct is connected to a source of supply by means of a pipe 19.

The three carbureting chambers communicate with a converging chamber 20 which may be termed a union by means of elbow 95 passageways 21 which extend at an angle from the upper portions of said chambers to the union. The passageways 21 are of less diameter than the carbureting chambers 10 and the lower ends of the elbow passageways 100 are tapered to form valve seats 22 which are controlled by tapered check valves 23. The vertical stems 24 of the check valves extend through the elbow passageways and are provided with enlargements or heads on their upper ends and coiled springs 25 surrounding the stems and interposed between the enlargements and the elbow passageways serve to yieldingly hold the valves in closed positions. The taper of the valves and the valve 110

seats permits a finer graduated opening than if the ordinary flat valve seats were used.

A flange coupling 26 threaded on the upper end of the converging chamber is provided for bolting the carbureter to the intake port of an internal combustion engine. This coupling is provided with an annular flange 27 spaced a short distance above the lower end of the coupling and the upper end portion of the converging tube is also provided with a similar flange 28 spaced a slight distance from the coupling flange to form an annular recess 29 to accommodate a cam ring 30. The cam ring is loosely mounted in the recessed portion between the two flanges and is provided with depending concentric cams 31, 32 and 33 which are adapted to engage the heads of the check valve stems 24 and force said heads downwardly in successive order when the said cam ring is turned.

A small auxiliary carbureter 34 is provided for initially starting the engine and for running at minimum speed. This auxiliary carbureter comprises a U-shaped mixing chamber 35 provided with a spring controlled air inlet, check valve 36 controlling the admission of air at one end of one of the stems of the chamber and a spring controlled check valve 37 controlling the discharge of vapor from the other end of the stem. The stem of this discharge check valve extends through the upper end of its stem of the chamber and is provided with an enlargement or head 38 which is adapted to be engaged by the auxiliary concentric cam 39 depending from the cam ring 30. The cams are so positioned with relation to the valve stem heads that when the cam ring is turned the auxiliary cam will first engage the auxiliary valve and open it gradually to its full open position and a further movement of the cam wheel will cause the cam 31 to engage the check valve 23 of the chamber 9 and gradually move it to full open position while the auxiliary valve still remains in open position. A further movement of the cam ring will cause the cam 32 to likewise open the valve 24 of the chamber 10, while the valve of the chamber 9 still remains in open position. A further movement of the cam ring will open the check valve 24 of the chamber 11 with all of the other similar valves held in open position. The auxiliary carbureter is supplied with volatile fluid through the duct 40 which communicates with the float chamber and the supply is controlled by means of an auxiliary needle valve 41. The carbureted fluid is drawn through the discharge pipe 42 which is adapted to also be connected to the intake port (not shown) of an internal combustion engine.

In operation the carbureter is properly connected to an internal combustion engine

and to a source of volatile fluid supply and in starting the engine or when desired to run at slow speed the cam wheel is turned to open the auxiliary carbureter valve. This operation will provide the engine with the necessary fuel to run at the desired speed. If it is now desired to increase the speed or power of the engine the cam ring is further turned to open the check valve of one of the carbureting chambers and this additional fuel will be supplied to the engine. A further turning of the cam ring will open the valves of the other carbureting chambers in successive order so that within the capacity of the engine any desired speed may be obtained.

The direct and short connections of the elbow passageways with the converging chamber serve to prevent condensation and consequently causes the engine to start easier.

From the foregoing description it will be seen that a multiple jet carbureter is provided which is well adapted for the purpose desired and permits of the greatest range and flexibility of control.

What I claim as my invention is:

1. A carbureter comprising a float chamber, an outlet chamber positioned adjacent to the float chamber, a plurality of carbureting chambers, nozzles for said carbureting chambers communicating with said float chamber, check valves controlling the admission of air to the carbureting chambers, ducts extending from said carbureting chambers to said outlet chamber, positively opening and closing valves controlling the passage of mixture to the ducts, and a movable cam member for successively engaging said valves to control the amount of mixture supplied to the outlet chamber.

2. In a carbureter, the combination, with a float chamber provided with a float for maintaining a predetermined fuel level, of a plurality of carbureting chambers positioned adjacent thereto and deriving fuel therefrom, air-inlet valves for said chambers, an outlet chamber, means connecting said carbureting chambers with said outlet chamber, a normally spring-pressed closed outlet valve for each carbureting chamber, and a member provided with valve-engaging cam portions for successively opening said valves to regulate the supply of mixture to the outlet chamber.

3. A carbureter, comprising a float chamber, a plurality of carbureting chambers extending alongside of the float chamber, nozzles extending from the float chamber to the carbureting chambers, check valves controlling the admission of air to the carbureting chambers, ducts extending from the carbureting chambers, valves controlling the ducts, and an adjustable member provided with a plurality of cam portions for

- successively engaging the duct valves to control the operation of the carbureting chambers.
4. A carbureter, comprising a float chamber, an auxiliary carbureter positioned adjacent to the float chamber and deriving volatile fluid therefrom, a plurality of carbureting chambers extending alongside of the float chamber, nozzles extending from the float chamber to the carbureting chambers, check valves controlling the admission of air to the carbureting chambers, ducts extending from the carbureting chambers, valves controlling the ducts, and an adjustable member provided with a plurality of cam portions for successively engaging the auxiliary carbureter and the duct valves to control the vapor discharged from the carbureting chambers.
5. A carbureter, comprising a float chamber, an auxiliary carbureter provided with an air inlet check valve and a valve controlled outlet duct, a nozzle extending from the float chamber to the auxiliary carbureter, a plurality of carbureting chambers positioned alongside of the float chamber, nozzles extending from the float chamber to the carbureting chambers, a converging chamber positioned above the float chamber, ducts extending from the carbureting chambers to the converging chamber, valves controlling the ducts, and a ring mounted on the converging chamber and provided with cam portions for successively engaging the outlet valve of the auxiliary carbureter and the duct valves to control the amount of mixture discharged from the auxiliary carbureter and the carbureting chambers.
6. A multiple nozzle carbureter, comprising a float chamber provided with a float for maintaining a predetermined fluid level,

a plurality of carbureting chambers positioned adjacent thereto and deriving fluid therefrom, check valves controlling the admission of air to the carbureting chambers, independent positively closing valves controlling the discharge of vapor from the carbureting chambers, and a cam member controlling the valves.

7. A multiple nozzle carbureter, comprising a float chamber provided with a float for maintaining a predetermined fluid level, a plurality of carbureting chambers positioned adjacent thereto and deriving fluid therefrom, check valves controlling the admission of air to the carbureting chambers, independent normally closed valves controlling the discharge of vapor from the carbureting chambers, and means positively controlling the successive opening of the valves.

8. In a carbureter, the combination, with a float chamber provided with a float for maintaining a predetermined fuel level, of a plurality of carbureting chambers, a nozzle in each of said carbureting chambers communicating with said float chamber, valves controlling the admission of air to said carbureting chambers, a mixture outlet, ducts connecting said outlet with each of said carbureting chambers, positively opening and closing valves for controlling the admission of mixture to the ducts, and means for controlling the successive operation of said valves.

In testimony whereof, I affix my signature, in presence of two witnesses.

WILLIAM H. KRUEGER.
